N. P. GREEN

COMBINED BLASTING GUN AND CHUTE

Filed June 27, 1924

Inventor,
NORRIS P GREEN
By Victor J. Evans
attorney.

UNITED STATES PATENT OFFICE.

NORRIS P. GREEN, OF MONTROSE, COLORADO.

COMBINED BLASTING GUN AND CHUTE.

Application filed June 27, 1924. Serial No. 722,777.

To all whom it may concern:

Be it known that I, NORRIS P. GREEN, a citizen of the United States, residing at Montrose, in the county of Montrose and 5 State of Colorado, have invented new and useful Improvements in Combined Blasting Guns and Chutes, of which the following is a specification.

This invention relates to improvements in 10 combined blasting guns and chutes.

The principal object of this invention is to provide means whereby ore may be blasted from a chute without the necessity of an operator exposing himself beneath the overhanging ore.

Another object is to provide means for discharging an explosive charge into an overhanging body of ore from a point outside of the chute.

20 A still further object is to provide a device of this character which is simple in construction, economical to manufacture, highly efficient in use, and one which will not materially alter the construction of the present chute.

Other objects and advantages will be apparent during the course of the following description.

In the accompanying drawings forming a 30 part of this specification, and in which like numerals are employed to designate like parts throughout the same,

Figure 1 is a side elevation of the blasting gun shown partly in section, disclosing the 35 same positioned on a beam of the ore chute, and

Figure 2 is a vertical cross-section of an ore chute showing the blasting gun positioned therebeneath.

40 Heretofore, when the ore in a chute has become packed it has been necessary to place a ladder of considerable length in the chute, and after the ladder has been thus positioned the operator has been compelled to climb 45 upwardly and place an explosive charge in the overhanging ore. This procedure is exceedingly hazardous and has often resulted in a disaster, and accordingly, to overcome this disadvantage and to eliminate the possibility 50 of danger I have devised my present invention wherein the numeral 5 designates an ore bin having a hopper 6 which hopper has a mouth 7 adapted to discharge into a chute 8. The bin may be supported in any 55 convenient manner and in the present instance, the supporting means comprises up-

rights 9 and 11 joined by suitable braces 12, 13, 14, 16 and 17.

At 18, I have shown an auxiliary brace 60 extending across the supporting frame-work, which brace is adapted to have secured thereto a clamp comprising two L-shaped members designated at 19 and 21. A clamping screw 22 is threaded in one leg of the L-shaped member 19 and carries a bolt 23 65 thereon. This bolt is adapted to contact the auxiliary brace 18, while the remaining leg of the other L-shaped member 21 contacts the opposite side of the brace.

A support 24 is resiliently mounted on 70 the L-shaped members by springs 26 surrounding pins 27 secured in the bottom of the support 24. A gun designated as a whole by the numeral 28 is pivoted at 29 to the support 24 and is provided with a recoil mechanism 31. A segment 32 acts in conjunction with the support 24 and forms a guide for swinging the gun 28 about its pivotal point 29.

A blasting charge 33 and a cartridge 34 80 is placed within the gun, the cartridge being exploded in the usual manner, that is, by the action of a hammer striking the concussion cap. A firing line 36 may be employed for operating the trigger if desired. At 37 I 85 have shown a small opening formed in the bottom of the chute 8 through which the charge in the gun may be discharged, as indicated in dotted lines of Figure 2.

The manner of operating my device is as 90 follows:

The entire device is clamped to the auxiliary brace and the gun aimed so as to discharge through the opening 37. It is to be observed that the direction the charge is to 95 take may be varied by swinging the gun upon its pivotal point. After proper adjustment has been made the trigger is pulled with the result that the explosive charge passes upwardly into the body of ore exploding when coming into contact with the same, thus breaking down the arch formation and allowing the ore to pass into the chute.

It is to be understood that the form of my 100 invention herewith shown and described is to be taken as a preferred example of the same, and that various changes in the shape, size and arrangement of parts may be resorted to without departing from the spirit 110 of the invention or the scope of the subjoined claims.

Having thus described my invention, I claim:—

1. In combination with an ore bin and its chute, of a charge carrying gun mounted beneath the chute, and means for firing said gun through said chute whereby the ore in the bin is released, substantially as and for the purpose described.
  2. In combination with an ore bin and its chute, of a charge carrying gun mounted beneath the chute, means connected to said chute for supporting said gun, and means for discharging said gun through said chute so as to engage the ore within said bin.
  3. In a device of the character described, the combination with an ore bin having a hopper positioned therein and a chute positioned therebelow, said chute having an ori-
- ifice substantially below said hopper, of a brace supported below said chute, a clamp secured to said brace, and a gun mounted on said clamp and adapted to be discharged through said chute and into said ore bin.
4. In a device of the character described, the combination with an ore bin having a hopper positioned therein and a chute positioned therebelow, said chute having an ori-
ifice substantially below said hopper, of a brace supported below said chute, a clamp secured to said brace, a gun mounted on said clamp and adapted to be discharged through said chute and into said ore bin, and re-coiling means carried by said gun, substantially as and for the purpose described.

In testimony whereof I affix my signature.

NORRIS P. GREEN.
